H. DE F. ARNOLD

VACUUM TUBE AMPLIFIER

Original Filed Sept. 3, 1915

Inventor:
Harold D. Arnold.
by W. E. Beatty, A. H. y

UNITED STATES PATENT OFFICE.

HAROLD DE FOREST ARNOLD, OF MAPLEWOOD, NEW JERSEY, ASSIGNOR TO WESTERN ELECTRIC COMPANY, INCORPORATED, OF NEW YORK, N. Y., A CORPORATION OF NEW YORK.

VACUUM-TUBE AMPLIFIER.

Original application filed September 3, 1915, Serial No. 48,873. Divided and application filed March 28, 1919, Serial No. 285,857. Divided and this application filed August 28, 1920. Serial No. 403,695.

To all whom it may concern:

Be it known that I, HAROLD D. ARNOLD, a citizen of the United States, residing at Maplewood, in the county of Essex and State 5 of New Jersey, have invented certain new and useful Improvements in Vacuum-Tube Amplifiers, of which the following is a full, clear, concise, and exact description.

This invention relates to vacuum tube amplifiers, and more particularly to arrangements for supplying space current thereto.

An object of this invention is to provide means whereby a plurality of vacuum tubes to be used as repeaters or amplifiers may be 15 supplied with space current from a single source, but in such a manner that current changes in one tube due to signals being repeated cannot be impressed upon another tube through said source.

20 With the arrangement shown herein, a single source of space current is used to energize both tubes of a two stage amplifier, and in the branches of the circuit therefore are interposed filters of series inductance and 25 shunt capacity to prevent alternating current from being bypassed therethrough.

The invention described and claimed herein is divided out of my applications, Serial No. 48,873, filed September 3, 1915, and Serial No. 285,857, filed March 28, 1919.

For further details, reference may be made to the accompanying drawings in which the single figure illustrates diagrammatically a two stage amplifier embodying the invention.

35 Referring to the drawing by reference numerals, the amplifier set comprises a tandem arrangement of two vacuum tubes 10 and 11 each having cathode 12, a grid or control electrode 13, and an anode 14. The cathodes 40 12 are maintained in a condition of thermionic activity by currents from sources 15.

The input circuit of tube 10 comprises terminals 16, 17, adapted to be connected to a suitable source of electric impulses to be 45 repeated, a resistance 18 bridged across the input electrodes, and a battery 19 adapted to maintain the grid electrode at a negative potential with respect to the cathode. Current between the anode and cathode is supplied from battery or other suitable source 20, the current passing in series through the inductance 21 and the transformer primary

22. A shunt condenser 23 provides a path for the alternating current.

The transformer secondary 24 has connected across its terminals a resistance 25, one end of which is connected to the cathode of tube 11. A connection from resistance 25 to the grid of tube 11 comprises the movable contact 26 and the battery 27, the function 60 of the latter being to provide the necessary negative potential on the grid.

Direct current is supplied to the tube 11 from source 20, through inductances 28 and 29, and grounds 30 and 31. Condenser 32 is 65 shunted across the direct current circuit. The output circuit for alternating current comprises the condenser 33 and the primary 34 of a transformer, the secondary 35 of which is adapted to be connected through 70 terminals 36 and 37 to any suitable receiving circuit.

In operation, the signals or other impulses, which are repeated and amplified by the tube 10, are impressed on the resistance 25 by 75 currents induced in the secondary coil 24. The input electrodes of the second tube are shunt to an adjustable part of the resistance 25, and therefore any desired proportionate part of the potential drop across the resistance 80 may be impressed between the input electrodes, with the result that the ratio of amplification may be varied between a predetermined maximum and zero.

The series inductances 21 and 28 and the shunt condensers 23 and 32 serve to prevent potential variations from the source or from either tube without being impressed through the supply circuit on the other tube.

While I have shown and described one embodiment of the invention, it is obvious that it may assume any desired form within the scope of the appended claims.

What is claimed is:

1. In combination, a plurality of vacuum tube repeaters, a common source of space current for said repeaters, the circuit between one of said repeaters and said source comprising series inductance, and a path comprising capacity bridged across said circuit between said source and said repeater. 100

2. In combination, a plurality of vacuum tube repeaters, a common source of space current for said repeaters, the circuit be-

tween each of said repeaters and said source comprising series inductance, and a path comprising capacity bridged across each of said circuits between said source and the 5 respective repeaters.

3. In combination, a plurality of vacuum tube repeaters, said repeaters being connected in multiple to a common source of space current, and means to prevent alternating currents from one of said repeaters from flowing in the portion of the space current circuit common to said repeaters.

4. In combination, a plurality of vacuum tube repeaters, said repeaters being connected in multiple to a common source of space current, and means to prevent alternating currents from flowing from each said repeaters to the others of said repeaters through the portion of the space current 20 circuit common to all.

5. In a multi-stage amplifier, a plurality of vacuum tubes connected in tandem, a common source of space current for said tubes, branch circuits connecting said source and said tubes, and a filter comprising series inductance in one of said circuits and a path containing capacity bridged across the circuit between one of said tubes and said source.

6. In a multi-stage amplifier, a plurality of vacuum tubes connected in tandem, a common source of space current for said tubes, branch circuits connecting said source and said tubes and a filter comprising series inductance in each of said circuits and a path containing capacity bridged across each of said circuits between each of said tubes and said source.

7. In combination, a plurality of vacuum 40 tube translating devices, a common source of potential for said vacuum tubes, a cir-

cuit connecting each of said tubes to said source containing series inductance and a path comprising capacity bridged across each of said circuits.

45

8. In combination, a plurality of vacuum tube translating devices, a common source of current for energizing said tubes, and a path comprising capacity bridged across each of the circuits connecting said tubes to said source.

50

9. In combination a plurality of vacuum tube translating devices, a common source of current for energizing said vacuum tubes, each of the circuits between said tubes and said source comprising series impedance, and a capacity effectively in shunt to said source for preventing interference between said tubes.

55

10. The combination in an amplifying system of a series of electron discharge amplifiers connected in cascade, each of said amplifiers having plate and grid circuits, a common source of current for supplying current to the plate circuits of all of said amplifiers in succession from the last to the first of said amplifiers, and filter connections between successive amplifiers of the series.

60

11. The combination in an amplifying system of a series of electron discharge amplifiers connected in cascade, each of said amplifiers having plate and grid circuits, a common source of current for supplying current to the plate circuits of all of said amplifiers, and filter connections between successive amplifiers of the series.

65

In witness whereof, I hereunto subscribe my name this 25th day of August A. D., 1920.

HAROLD DE FOREST ARNOLD.
